No. 826,197.

PATENTED JULY 17, 1906.

C. G. SHEPHERD.

HASP LOCK.

APPLICATION FILED OCT. 5, 1905.

UNITED STATES PATENT OFFICE.

CHESTER G. SHEPHERD, OF RUTLAND, ILLINOIS.

HASP-LOCK.

No. 826,197.

Specification of Letters Patent.

Patented July 17, 1906.

Application filed October 5, 1905. Serial No. 281,505.

To all whom it may concern:

Be it known that I, CHESTER G. SHEPHERD, a citizen of the United States, residing at Rutland, in the county of LaSalle and State of Illinois, have invented new and useful Improvements in Hasp-Locks, of which the following is a specification.

In my pending application, Serial No. 275,797, filed August 25, 1905, a seal-lock is shown and described and claimed applicable to a fastening, such as a hasp and staple, and intended particularly for use on railway freight-cars.

The invention forming the subject of the present application is an improvement or modification of the device referred to and is characterized particularly by the use of a key-lock for controlling the bolt of the hasp. Some of the seal-lock features are, however, retained, as will more fully appear from the following.

The present invention is illustrated in the accompanying drawings.

Figure 1 is a plan or face view; Fig. 2, a plan view with the top plate removed, and Fig. 3 a section on the line 3-3 of Fig. 1.

Referring specifically to the drawings, the hasp-casing comprises a back plate 6 and a top plate 7, riveted together. The back plate is recessed to form a space for the tumblers and other parts of the lock and also for the lock-controlled devices which operate the locking-pin. The pin is indicated at 8 and slides within a tubular casing 9, formed by cored bosses on the face of the casing. It moves across the slot 10, through which the staple on the door-post extends when the hasp is fastened. The hasp is fastened to the door by a staple extending through a hole 14 in the end of the casing.

The pin 8 is operated by a swinging piece 15, which turns on a stud 16 within the casing. This piece has a tongue 17, which extends into a slot 18 in the pin, and when the piece is turned or swung the pin is raised or lowered accordingly to unlock or lock the hasp. At the side opposite the tongue 17 the piece 15 has a notch 13, which receives a lug 19, projecting from a finger-piece by means of which the pin is manipulated. This finger-piece comprises a ring 21, by which it may be taken hold of and from which projects an upper branch 22 and a lower branch 23. The upper branch has a hole 24 to receive a wire seal, a slot 25 to receive a strap seal, and a hole 26 to receive the shackle of a pad-

lock or the wire of a so-called "Keystone" seal. The lower arm fits through an opening in the lower edge of the casing and extends into the recess containing the lock and the piece 15, and, as said before, said arm has a lug 19, which engages the notch of said piece, so that when the finger-piece is slid up or down the piece 15 is turned accordingly and the bolt moved in or out. The space between the upper and lower arms 22 and 23 is of proper width to embrace the upper plate of the casing which fits therebetween, so that the upper arm is on the outside of the casing and the lower arm is on the inside thereof, and the finger-piece will slide up and down, as indicated, to operate the pin.

The lock may be sealed in various ways, as referred to in my former application, by means of seals of one kind or another inserted through the openings 24, 25, or 26 in the finger-piece and through corresponding openings 29, 30, and 31 in ribs 28, which stand upon the face-plate on opposite sides of the upper branch of the finger-piece; but the present case is more particularly concerned with the key-lock. This lock has a sliding bolt 30 with a projection 31, which engages in a notch 32, formed in the edge of the lower branch 23 of the finger-piece. This bolt is advanced by a spring 33, so that it will lock without a key, and may be unlocked by means of a key inserted in the key-hole 34, the operation being controlled by pivoted spring-tumblers 35.

When the projection 31 is engaged in the notch 32, the finger-piece cannot be pulled out, and consequently the pin cannot be retracted; but by the use of the proper key the bolt of the lock will be retracted, disengaging the projection 31 from the notch 32 and allowing the finger-piece to be pulled down to lift the pin and release the hasp and staple.

It will be noticed that the hasp-pin is retained in the casing at all times and cannot come out. The possibility of using several kinds of locks or seals makes the device particularly valuable for railroad use. It will be understood that the size and proportions of the device may be varied according to the kind of use it is to be put to. The key-lock may be used with or without one of the seals, various kinds of seals being used according to the kind in use wherever the car happens to be.

What I claim as new, and desire to secure by Letters Patent, is—

1. A hasp-lock having a casing, a slidable pin therein arranged to engage the staple, a lever in the casing connected to the pin, a finger-piece having a branch projecting into the casing to engagement with the lever, and a lock in the casing, the bolt of which engages the finger-piece.
2. A hasp-lock comprising a casing containing a pin arranged to engage a staple, a finger-piece operatively connected to the pin and having a part inside and a part outside of the casing, the latter part having openings

to receive a seal, and a lock inside the casing having a bolt engageable with said inside part of the finger-piece, to prevent movement thereof. 15

In testimony whereof I have signed my name to this specification in the presence of two subscribing witnesses.

CHESTER G. SHEPHERD.
